FIG. 3.

FIG. 4.

JOHN USNIK

By *C. Snow & Co.*
Attorneys.

UNITED STATES PATENT OFFICE.

JOHN USNIK, OF LOS ANGELES, CALIFORNIA.

PHOTO-PRINTING CABINET.

Application filed May 16, 1925. Serial No. 39,816.

This invention relates to photo printing cabinets, and aims to provide a novel form of cabinet to facilitate the making of photographic prints from films or plates.

5 An important object of the invention is to provide a switch mechanism controlled by the operation of the film or plate carrier to cause the lamps in the lamp chamber to be lighted when the film or plate carrier is moved to a position to close the cabinet.

Another object of the invention is to provide means whereby the plate or film holder will automatically adjust itself when a plate is positioned thereon, thereby compensating 15 for the increased thickness of a photographic plate over a film.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

Referring to the drawings:

Figure 1 is a vertical sectional view through a cabinet constructed in accordance 30 with the invention, the cover or plate holder being shown in its open position.

Figure 2 is a vertical sectional view taken at right angles to Figure 1.

Figure 3 is a sectional view taken on line 35 3-3 of Figure 1.

Figure 4 is an enlarged sectional view illustrating the upper portion of the cabinet.

Figure 5 is a fragmental sectional view 40 illustrating the connection between the film or plate holder and the cabinet body.

Figure 6 is a fragmental plan view illustrating the hinged connection between the film or plate holder and cabinet body.

Referring to the drawings in detail, the 45 body portion of the cabinet is indicated generally by the reference character 5 and includes an upper lamp chamber 6, and a lower compartment 7 which is normally closed by means of the hinged closure 8, the rear wall 50 of the compartment 7 being provided with openings 9 to insure ventilation within the compartment, to maintain the paper and developing materials placed therein, in proper condition.

55 The lining for the lamp chamber 6 is indicated at 10, and is formed preferably of re-

flecting material so that the light rays from the lamps 11 positioned therein, will be projected upwardly onto the film or plate supported thereabove.

60 Disposed above the lamp chamber 6 and providing the upper wall thereof, is a transparent wall 12 formed preferably of glass, the edges thereof being held between the securing members 13.

65 Bars 14 are arranged at the upper end of the cabinet and are provided with cutout portions to accommodate the glass member 15 which has its surfaces treated to render the same opaque.

70 The upper portion of the cabinet embodies a frame 16 that is connected to the body of the cabinet by means of the hinge 17, and as shown, this frame is provided with a gasket 18 adapted to fit over the edges of the glass 75 member 15 to insure a light-proof connection between the frame and glass member 15.

75 The upper surface of the frame 16 is formed with a cut out portion to accommodate the glass supporting member 19 against which the backing member 20 engages when the backing member is moved to clamp a film or plate in position to accomplish the printing operation.

80 A bar 21 is positioned over the frame and engages the glass supporting member 19 to hold it in position at all times. This bar 21 also provides means for connecting the backing member to the cabinet, and as shown, a hinge indicated at 22 is provided for hinged- 85 ly connecting the backing member 20 to the bar 21.

85 In order that prints and films may be properly positioned, the backing member 20 embodies hingedly connected sections, the 90 inner surfaces thereof being supplied with a felt member 23 to insure pressure on the film or plate engaged thereby.

95 Spaced arms indicated at 24 extend from the backing member 20 and are connected by 100 means of the rod 25. Pivotedly connected with the cabinet, at 26, and extended between the arms 24 is an arm 27 that has its forward end extended to a position beyond the forward wall of the cabinet so that the 105 same may be readily grasped by the operator to position or remove a film.

110 Supported under the arm 27 is a latch member 28 that is adapted to cooperate with the keeper 29 to hold the arm 27 to its active position, when the film or plate has been positioned and the arm moved down.

wardly to force the backing member into engagement with the film or plate.

Spring members 30 are carried by the arm 27 and are adapted to engage the sections of the backing member to exert a downward pressure thereon when the backing member has been moved to its active position. In order that the backing member together with the arm 27 will be restricted 10 in its rearward movement, a stop 31 is provided which stop is disposed in the path of travel of the backing member and arm as shown by Figure 2 of the drawings.

Formed in the bar 21 are openings 15 adapted to accommodate the bolts 32 that are secured to the frame 16, the lengths of the bolts being such as to provide a space between the heads of the bolts and the bar 21, which space accommodates the coiled 20 springs 33 that exert a downward pressure on the bar 21. Thus it will be seen that due to this construction, the bar 21 may move upwardly to adapt the device for use in printing by the use of photographic 25 plates.

The lamps 11 are in circuit with a suitable source of electric energy not shown, the circuits to the lamps being controlled by the switch members 34, all of which switch 30 members are in circuit with a master switch including contact member 35 and contact member 36 carried by the arm 27. A main switch 37 is also in circuit with the master switch and switches 34, to the end that 35 when the switch member 37 has been moved to close the circuits between certain switch members 34, the master switch must be operated by moving the arm 27 to a position as shown by Figure 4 of the drawing, whereupon the lamps which have been brought into operation by the movements 40 of the switches 34 will be lighted, to supply

light sufficient to print pictures from films positioned on the glass supporting member 19.

In order that the frame 16 will be held against rearward movement, pivoted arms 38 have connection with the frame as shown by Figure 2. Pivoted exteriorly of the cabinet and arranged at opposite 50 sides thereof are shelves 39 designed to support printing paper or other material employed in the printing of photographs from plates or films.

In view of the foregoing detail description, it is thought that a further detail description as to the operation of the device is unnecessary.

I claim:—

A photographic printing cabinet including a body portion, said body portion being divided into an upper lamp chamber and a lower compartment, lamps in the lamp compartment, a pair of contact members extending upwardly from the body portion, 65 a master switch, wires for providing circuits between the contact points, master switch and lamps, a movable frame for supporting articles to be printed, mounted at the upper portion of the body portion and 70 having an opening through which the contact points extend, backing members adapted to engage an article supported by the frame, to engage the articles and hold them to the frame, a pivoted arm for engaging the backing members to hold the 75 backing members tightly against the frame, and a contact member carried by the arm and adapted to engage the contact points to complete circuits to the lamps.

In testimony that I claim the foregoing as my own, I have hereto affixed my signature.

JOHN USNIK.
